DRY MATERIAL MIXING MACHINE

Louis G. Tocci, Leominster, Mass.

Application September 6, 1957, Serial No. 682,387

8 Claims. (Cl. 259—57)

This invention relates to improvements in method and apparatus for mixing together powdered or granular materials, such as basic or neutral plastic molding materials and plastic coloring materials, by tumbling the materials together.

The primary object of the invention is to provide a method of and tumbler apparatus for mixing together different powdered or granular materials, which enable eliminating the present necessity of transferring the basic or neutral material from bags in which the material is supplied, into drums on a tumbler machine, tumbling the drums on the machine to produce mixing, and then transferring the mixed material back into the bags, so that substantial savings in time, labor, and wastage of material are obtainable.

Another object of the invention is to provide, for use on a conventional tumbler machine, improved bag holders composed of stationary sections and hinged sections which can be opened relative to the stationary sections for easier and quicker loading and removing bags.

A further object of the invention is to provide closure containers arranged to be inserted in the open tops of bags so as to form closures for the bags, and which enlarge the capacities thereof so as to enable free tumbling of the materials in the bags by a tumbler machine, the closure containers being readily removable upon completion of a tumbling operation, to enable the bags containing mixed materials to be closed and put in stock ready for use.

A still further object of the invention is to provide in bag holders of the character indicated above, clamping means for engaging the bags in the regions of the containers, so as to securely clamp the containers inserted in the bags and so as to securely clamp the bags and their containers in the holders.

Other important objects and advantageous features of the invention will be apparent from the following description and the accompanying drawings, wherein, for the purposes of illustration only, a specific form of the invention is set forth in detail.

In the drawings:

Figure 1 is a side elevation of a tumbler machine equipped with bag holder assemblies of the present invention containing material filled bags in which containers of the present invention are clamped.

Figure 2 is a top plan view of Figure 1.

Figure 3 is a vertical transverse section taken on the line 3—3 of Figure 1.

Figure 4 is an enlarged horizontal section taken on the line 4—4 of Figure 1, hinged sections of holders being shown in closed positions in full lines and in open positions in phantom lines.

Figure 5 is a fragmentary vertical transverse section taken on the line 5—5 of Figure 4.

Figure 6 is an enlarged fragmentary vertical transverse section taken on the line 6—6 of Figure 4, showing a

2

hinged section clamp in engaged position in full lines and in disengaged position in phantom lines.

Figure 7 is a perspective view of a holder assembly with the hinged sections of its holders in open position.

5 Referring in detail to the drawings, wherein like numerals designate like parts through the several views, the numeral 10 generally designates a conventional tumbler comprising a housing 12 mounting on its top two coaxial rotary shafts 14 driven by a motor 16 within the housing 12. Mounted on and fixed to the shafts at opposite ends of the housing 12 at right angles to each other are bag holder assemblies 18 of the present invention.

10 Each of the bag assemblies 18 comprises a flat elongated oval bottom plate 20 from which rise two cylindrical holders 22 concentric to the rounded ends 21 of the bottom plate 20 and composed of inner semi-cylindrical stationary sections 24, and outer semi-cylindrical hinged sections 26. The stationary sections 24 comprise diametrically opposed vertical end bars 28 and 30 which are suitably fixed at their lower ends to the bottom plate 20 along the longitudinal center line of the bottom plate, lower semi-circular bands 32 fixed at their ends to the end bars 28 and 30 at points spaced upwardly from the bottom plate 20, and relatively wide semi-circular upper or clamping bands 34 fixed on the upper ends of the end bars 28 and 30, with circumferentially spaced vertical bars 36 extending between and secured to the lower and upper bands 32 and 34. The adjacent ends of the upper clamping bands 34 are connected together by a connector plate 38.

15 The hinged sections 26 comprise lower semi-circular bands 40 and upper semi-circular clamping bands 42 which are spaced and connected by circumferentially spaced vertical bars 44, the vertical spacing of the lower and upper bands 40 and 42 being the same as that of the lower and upper bands 32 and 34 of the stationary sections 24. On the outer ends of the upper clamping bands 42 are radially outwardly projecting clamp lugs 43 which are approximately half the length of the connector plate 38, which the lugs 43 engage in the closed positions of the hinged sections. The inward ends of the lower and upper bands 40 and 42 of the hinged sections 26 are hinged, as indicated at 46 and 48 to the outward ends of the lower and upper bands 32 and 34 of the stationary sections 24.

20 A U-shaped clamp, generally designated 50, and shown in detail in Figure 6, has an inward leg 52 which is horizontally pivoted at the lower end, as indicated at 54, to the inward side of the connector plate 38, and threaded at right angles through the outer leg 56 of the clamp is a clamping screw 58 having a head 60 on its inward end, and a handle 62 on its outer end. As shown in Figures 4 and 7, the clamping screw head 60 bears against the clamp lugs 43 when the hinged sections 26 are closed, for maintaining their closed positions, and is retractable therefrom to enable the clamp to be swung inwardly out of the way, as shown in phantom lines in Figure 7, to free the hinged sections 26 to be opened.

25 45 Fixed to the outer sides of the upper bands 42 of the hinged sections 26 near the inward ends thereof and reaching thereabove are inverted L-shaped brackets 64 having arms 66 on their upper ends which extend radially inwardly to retainably engage the closure containers 68 which are inserted into the open upper ends 70 of material containing bags 72 of paper or other flexible material.

30 50 Means for mounting a holder assembly 18 on a shaft 14 of the tumbler machine 10 comprises a horizontal bar 74 extending between and along the inward sides of the holders 22 and having bent end portions 76 secured to the upper bands 42 of the stationary sections 24. A

35 55 60 65 70 75 80 85 90 95

60 65 70 75 80 85 90 95

65 70 75 80 85 90 95

reinforcing channel bar 78 extends along the intermediate part of the bar 74 and has its web secured to the bar 74 and has the edges of its flanges 80 secured in a suitable manner to the upper bands 42 of the stationary sections 26. A vertical channel brace bar 82 has its upper end secured to the midpoint of the channel bar 78 and its lower end secured to the bottom plate 20. A diagonal brace 84 has its outer end elevated and secured to the connector plate 38 and its depressed inward end 86 secured, as indicated at 88, to the vertical brace bar 82 at a point spaced below the channel bar 78, as shown in Figure 1. A socket 90, positioned at an upward angle relative to the vertical brace bar 82 is engaged on the tumbler machine shaft 14 and is secured thereon by a set screw 92. The socket 90 is secured to the inward side of the vertical brace bar 82 by a plate 94 positioned below the channel bar 78 and secured to the vertical brace bar 82 by the means 88 and by similar means 96, and a brace 98 extends between the socket 90 and a lower part of the plate 94. By means of this arrangement, the holder assemblies 18 are inwardly tilted relative to the axis of the tumbler machine shafts 14, as shown in Figures 1 and 2.

The closure containers 68 are cylindrical and of diameters to fit snugly into the open upper ends 70 of bags 72, and comprise sidewalls 100, a closed top wall 102, and an open lower end 104. The major part of the closure container is, as shown in Figure 5, inserted in the bag, so as to close the bag and enlarge the capacity of the bag and so as to provide a material tumbling space 106 above the open upper edge 70 of the bag. The closure container extends down below the upper clamping bands 34 and 42 of the holders 22, and on the inner sides of these upper bands are compressible pads 108 of foam rubber or the like whose inside diameters are slightly less than the outer diameter of the part of the bags in which the closure containers extend, so that when the hinged sections 26 are closed around bags having closure containers in place therein, the pads 108 are compressed and bear compressively and frictionally against the outsides of the bags and thereby hold the bags against shifting in the holders 22 and retain the closure containers 68 in the bags, when the tumbler machine 10 is operated with the bracket arms 66 engaged over the top walls of the containers.

Fixed on the outsides of the endwalls 100 of the closure containers 68 near their closed upper ends are diametrically opposed loop handles 110, which facilitate handling and manipulating the closure containers 68.

From the foregoing it will be seen that the method of the present invention comprises opening a paper or like material bag of basic or neutral material, pouring therein a desired quantity of additive material, such as coloring material, inserting part way into the open top of the bag an open-bottom closure container, so as to provide tumbling space for the material above the top of the bag, then securing the bag and closure container assembly in a holder of a tumbling machine, and operating the machine to effect the desired mixing of the materials in the bag.

While I have shown and described herein specific forms of method and apparatus of the invention, it is to be understood that any change or changes in the steps and operation of the method, and in the forms of and relative arrangements of components of the apparatus can be made and are comprehended as within the scope of the invention as defined by the claims appended hereto.

What is claimed is:

1. In a tumbler machine, a housing having power-driven horizontal coaxial rotary shafts extending from opposite ends thereof, holder assemblies mounted on and fixed to the shafts, said holder assemblies each comprising a bottom plate, cylindrical bag holders fixed to and rising from opposite ends of the bottom plate, and means for mounting the assemblies on the shafts, each of said

holders comprising stationary semi-cylindrical sections and semi-cylindrical hinged sections hinged on each of the stationary sections, a connecting plate extending between and secured to the stationary sections, clamping lugs on the outer ends of the hinged sections arranged to bear against the connector plate in the closed positions of the hinged sections, and a clamp mounted on said connector plate for clamping said clamping lugs against the connector plate.

10 2. In a tumbler machine, a housing having power-driven horizontal coaxial rotary shafts extending from opposite ends thereof, holder assemblies mounted on and fixed to the shafts, said holder assemblies each comprising a bottom plate, cylindrical bag holders fixed to and rising from opposite ends of the bottom plate, and means for mounting the assemblies on the shafts, each of said holders comprising stationary semi-cylindrical sections and semi-cylindrical hinged sections hinged on each of the stationary sections, said mounting means comprising a horizontal bar extending between and fixed to the stationary sections, a vertical bar extending between and secured to said bottom plate and said horizontal bar, and a socket secured to and extending laterally from said vertical bar.

25 3. In a tumbler machine, a housing having power-driven horizontal coaxial rotary shafts extending from opposite ends thereof, holder assemblies mounted on and fixed to the shafts, said holder assemblies each comprising a bottom plate, cylindrical bag holders fixed to and rising from opposite ends of the bottom plate, and means for mounting the assemblies on the shafts, each of said holders comprising stationary semi-cylindrical sections and semi-cylindrical hinged sections hinged on each of the stationary sections, said stationary sections comprising longitudinally spaced inner and outer vertical end bars fixed to and rising from said bottom plate, lower semi-cylindrical bands secured at their ends to the inner and outer end bars on a level spaced above the bottom plate, upper semi-cylindrical clamping bands secured at their ends to the inner and outer end bars, said upper clamping bars being spaced above said lower bands, said hinged sections comprising lower semi-cylindrical bands, upper semi-cylindrical clamping bands, vertical spacing bars secured at opposite ends to the lower and upper bands and vertically spacing the same like the lower and upper bands of the stationary sections, the bands of the stationary sections and the hinged sections having inner and outer ends, hinge means hinging the inner ends of the hinge section bands on the outer ends of the stationary section bands, and means for retaining the hinged sections in closed relation to the stationary sections.

4. In a tumbler machine, a housing having power-driven horizontal coaxial rotary shafts extending from opposite ends thereof, holder assemblies mounted on and fixed to the shafts, said holder assemblies each comprising a bottom plate, cylindrical bag holders fixed to and rising from opposite ends of the bottom plate, and means for mounting the assemblies on the shafts, each of said holders comprising stationary semi-cylindrical sections and semi-cylindrical hinged sections hinged on each of the stationary sections, said stationary sections comprising longitudinally spaced inner and outer vertical end bars fixed to and rising from said bottom plate, lower semi-cylindrical bands secured at their ends to the inner and outer end bars on a level spaced above the bottom plate, upper semi-cylindrical clamping bands secured at their ends to the inner and outer end bars, said upper clamping bands being spaced above said lower bands, said hinged sections comprising lower semi-cylindrical bands, upper semi-cylindrical clamping bands, vertical spacing bars secured at opposite ends to the lower and upper bands and vertically spacing the same like the lower and upper bands of the stationary sections, the bands of the stationary sections and the hinged sections having inner and outer ends, hinge means hinging the inner ends of

the hinged section bands on the outer ends of the stationary section bands, and means for retaining the hinge sections in closed relation to the stationary sections, said retaining means comprising lateral clamping lugs on the outer ends of the upper clamping bands of the hinged sections, a connector plate extending between and secured to the inner ends of the upper clamping bands of the stationary sections, said lugs being arranged to bear against said connector plate in the closed positions, and clamping means mounted on said connector plate for clamping said lugs against the connector plate.

5. In a tumbler machine, a housing having power-driven horizontal coaxial rotary shafts extending from opposite ends thereof, holder assemblies mounted on and fixed to the shafts, said holder assemblies each comprising a bottom plate, cylindrical bag holders fixed to and rising from opposite ends of the bottom plate, means for mounting the assemblies on the shafts, each of said holders comprising stationary semi-cylindrical sections and semi-cylindrical hinged sections hinged on each of the stationary sections, said stationary sections comprising longitudinally spaced inner and outer vertical end bars fixed to and rising from said bottom plate, lower semi-cylindrical bands secured at their ends to the inner and outer end bars on a level spaced above the bottom plate, upper semi-cylindrical clamping bands secured at their ends to the inner and outer end bars, said upper clamping bars being spaced above said lower bands, said hinged sections comprising lower semi-cylindrical bands, upper semi-cylindrical clamping bands, vertical spacing bars secured at opposite ends to the lower and upper bands and vertically spacing the same like the lower and upper bands of the stationary sections, the bands of the stationary sections and the hinged sections having inner and outer ends, hinge means hinging the inner ends of the hinged section bands on the outer ends of the stationary section bands, and means for retaining the hinged sections in closed relation to the stationary sections, and compressible pads lining the upper clamping bands of the stationary and hinged sections.

6. In combination, a tumbler machine having a rotary horizontal shaft, a bag holder assembly mounted on said shaft to rotate therewith, said holder assembly comprising a cylindrical bag holder having a stationary semi-cylindrical section and a hinged semi-cylindrical section hinged on said stationary section, means for releasably clamping said hinged section in closed relation to said stationary section, a bottom plate secured on said stationary section and extending under said hinged section, and compressible pads lining said stationary and hinged sections.

7. In combination, a tumbler machine having a rotary horizontal shaft, a bag holder assembly mounted on said shaft to rotate therewith, said holder assembly comprising a cylindrical bag holder having a stationary semi-cylindrical section and a hinged semi-cylindrical

section hinged on said stationary section, means for releasably clamping said hinged section in closed relation to said stationary section, a bottom plate secured on said stationary section and extending under said hinged section, compressible pads lining said stationary and hinged sections, a flexible comminuted material containing bag in said holder and resting upon said bottom plate, said bag having an open upper end located above the holder, a relatively rigid cylindrical closure container having a sidewall, a closed upper end and an open lower end, said closure container being partially inserted in the upper end of the bag with the closed upper end spaced above the upper end of the bag and with its open lower end below said compressible pads, the space in the closure container between the upper end of the bag and the closed upper end of the container defining a material tumbling space, said clamping means serving to engage the compressible pads compressively and frictionally with the outside of the bag and clamp the bag on the closure container and retain the closure container in place in the bag.

8. In combination, a tumbler machine having a rotary horizontal shaft, a bag holder assembly mounted on said shaft to rotate therewith, said holder assembly comprising a cylindrical bag holder having a stationary semi-cylindrical section and a hinged semi-cylindrical section hinged on said stationary section, means for releasably clamping said hinged section in closed relation to said stationary section, a bottom plate secured on said stationary section and extending under said hinged section, compressible pads lining said stationary and hinged sections, a flexible comminuted material containing bag in said holder and resting upon said bottom plate, said bag having an open upper end located above the holder, a relatively rigid cylindrical closure container having a sidewall, a closed upper end and an open lower end, said closure container being partially inserted in the upper end of the bag with its closed upper end spaced above the upper end of the bag and with its open lower end below said compressible pads, the space in the closure container between the upper end of the bag and the closed upper end of the container defining a material tumbling space, said clamping means serving to engage the compressible pads compressively and frictionally with the outside of the bag and clamp the bag on the closure container and retain the closure container in place of the bag, and brackets on and rising above said hinged sections having lateral arms overlying and engaging the closed upper end of the closure container.
